HEAT CONDUCTIVE INSULATING SUPPORT

Cormack E. Boucher, Seattle, Wash.

Application August 10, 1953, Serial No. 373,277

6 Claims. (Cl. 250—89)

The present invention relates to a heat conductive, electrically insulating supporting device, and more particularly to a device for supporting X-ray tubes or other electronic tubes and the like, and for conducting away the heat generated during the operation thereof.

During operation of an X-ray tube considerable heat is generated at the anode of the tube due to the impact thereon of the impinging electrons from the cathode. Unless some measures are taken to conduct away this heat, the temperature of the anode, which is generally formed of copper, may rise to an extent where occluded gases may be liberated or even rise above the melting point of copper, thus destroying the tube. It has been customary heretofore, and especially with tubes operating at relatively high potentials, to mount the X-ray tube within a housing filled with oil to which the heat will be transferred, the oil also serving as electrical insulation between the tube and the housing. Such arrangements, however, have been somewhat unsatisfactory since the insulating oils heretofore available have a relatively poor heat transfer efficiency. Also, the dielectric strength of such oils is greatly impaired by heating thereof. Moreover, the use of such oils complicates the replacement of an X-ray tube when that is necessary.

Recently there have been available certain liquid fluorochemicals having excellent dielectric properties not impaired at elevated temperatures and which fluorochemicals have a very low viscosity whereby convection currents are easily established to transfer heat effectively and efficiently. However, such fluorochemicals are relatively expensive and the cost of filling an entire housing as has been done heretofore is prohibitive in most instances.

It is an important object of the invention to provide new and improved means for supporting a pair of electrically insulated members in heat conductive relationship.

More particularly, it is an object of the invention to provide a new and improved device for supporting an X-ray tube within a housing and through which device heat from the anode may be efficiently transferred to the housing.

A further object is to provide an electrically insulating, heat conductive X-ray tube support which facilitates replacement of tubes in X-ray apparatus.

Other objects and advantages of the invention will become more apparent hereinafter.

In accordance with an illustrated embodiment of the invention, a support device is provided comprising a sealed envelope of a dielectric having extending therefrom in spaced relation a pair of heat conducting elements. One of the elements is adapted to be connected to an electrical member such as the anode of an X-ray tube, and the other to a housing or other supporting member to which heat is to be transferred and in relation to which the electrical member is to be supported. The envelope is filled substantially with an electrically insulating liquid stable at high temperatures and having

high heat transfer efficiency for transferring the heat from one of the supporting members to the other by convection currents.

In the drawings,

5 Fig. 1 is a longitudinal, sectional view of one embodiment of the invention showing it connected to the anode of an X-ray tube;

Figure 2 is a fragmentary end elevation showing details of the connection of the device of Fig. 1 to the X-ray tube anode;

10 Fig. 3 is a side elevation of a further embodiment of the invention;

Fig. 4 is a longitudinal sectional view of another embodiment of the invention;

15 Fig. 5 is a view partly in section showing a still further embodiment of the invention;

Fig. 6 is a sectional view taken substantially along line 6—6 of Fig. 5; and

20 Fig. 7 is a sectional view taken substantially along line 7—7 of Fig. 5.

Referring first to Figs. 1 and 2, a device made in accordance with the invention and indicated generally at 9 is illustrated in connection with an X-ray tube comprising an envelope 10, from one end of which projects 25 the stem 11 of the anode (not shown), an electrical lead 12 being shown attached to the end of the anode stem for applying the potential difference between the anode and cathode (not shown). The device of the invention is shown in Figs. 1 and 2 as supporting the anode end 30 of the tube below a housing 13 or other member to which heat may be transmitted from the anode. It is to be understood that the cathode end of the tube may be supported in any suitable manner. The device of the invention comprises an elongated, vertically arranged 35 container, chamber or envelope 14 formed of glass or other material having a high dielectric strength. Extending into the lower end of the envelope is a heat conducting element 15, and extending into the upper end of the envelope is a further heat conducting element 40 16, the elements being sealed to the envelope. As shown, the opposite ends of the envelope may be turned inwardly to form reentrant sleeve portions 17 on which the heat conducting elements are mounted by means of a corresponding mounting flange 18 brazed or otherwise 45 suitably connected to the heat connecting element 15 or 16 and sealed to the reentrant portion 17 by a conventional glass-to-metal seal. The portion of each of the heat conducting elements 15, 16 projecting into the envelope 14 comprises a heat radiating body and is provided with a plurality of fins 19, 20, respectively, to increase the effective heat radiating surface of the respective element. Preferably the fins 19, 20 are axial radiating fins, as shown, rather than annular, to permit more effective circulation of the liquid convection currents.

50 Preferably the heat conducting elements 15, 16 are formed of copper or other material having good heat conductivity characteristics.

The portion of the lower heat conducting element 15 extending outwardly of the envelope 14 is formed with a split eye 23 adapted to receive the anode stem 11, the eye being adapted to be clamped tightly to the stem 11 by means of a bolt and nut 24 cooperatively arranged therewith. The upper heat conducting element 16 is secured to the housing 13 in any suitable manner such as, for example, by a stud bolt 25.

Sealed within the envelope 14 is a suitable nonionizing liquid indicated at 26, preferably a liquid having high heat transfer efficiency characteristics. Preferably the 70 volume of the liquid 26 is slightly less than the total volume of the envelope 14 so as to provide a space above the liquid for the expansion of any vapors there.

from as the temperature of the liquid and its vapors rises and to permit boiling of the liquid. Preferably, also, the volume of the liquid 26 is sufficient so as substantially to cover the radiating fins 19, 20 in any position of the device.

The heat generated at the target of the anode will be conducted through the anode stem 11 and transmitted to the lower heat conducting element 15 through the fins 19 thereof, and thence to the liquid 26 within the envelope 14. Heating of the liquid will establish convection currents therein, causing the hot liquid to rise and transfer its heat to the fins 20 of the top heat conducting element 16 which will in turn lose its heat to the housing 13 from whence it can be dissipated in any suitable manner.

Referring now to Fig. 3, a further embodiment of the invention is shown in connection with an X-ray tube comprising an envelope 31 from one end of which projects the stem 32 of the anode formed of copper or other suitable material. The electrical connection to the anode is indicated at 33. In this instance the anode stem 32 is provided with a plurality of heat radiating fins 34 at its outer end and which outer end is sealed within the envelope 35 of a heat transmitting and supporting device 40. The envelope 35 is preferably glass and may be formed with reentrant sleeve portions 36, 37 on one of which the anode stem 32 may be mounted as indicated at 38. Mounted in the opposite end of the envelope 35 is a heat conducting element 39 sealed to the reentrant sleeve portion 37 in a suitable manner and having a plurality of heat absorbing fins 43 formed on the portion thereof within the envelope 35. The outer end of the heat conducting element 39 may be adapted to be connected to any supporting member or cold body (not shown) to which heat may be transmitted for eventual dissipation. The envelope 35 is filled with an electrical insulating, heat conducting liquid 44 which preferably, as in the case of the previously described embodiment, does not completely fill the envelope 35 but is sufficient in amount substantially to cover the fins 34, 43.

In the embodiment of the invention illustrated in Fig. 4, the heat transfer device is formed integrally with an X-ray tube or generator comprising an envelope 50 and an anode 51. Only a fragmentary portion of the envelope and anode are shown, it being understood that only the design of the illustrated portions is of concern to the present invention. The envelope 50 is preferably of glass or other dielectric. The anode 51 is supported on an end wall 52 sealed in a suitable manner to the envelope 50. If the envelope is of glass, the end wall 52 is preferably of a metal alloy having the same expansion coefficient as glass. Electrical connection may be made to the anode through a lead indicated at 53 secured to a suitable lug 54 formed on the end wall 52. The anode 51 includes a stem portion 55 extending through the end wall 52 and provided with a plurality of heat radiating fins 56. The anode stem portion 55 is soldered, brazed, or otherwise suitably sealed to the end wall 52.

Sealed at one end to the end wall 52 is an elongate tubular member 57 formed of a suitable dielectric such as glass or plastic and positioned substantially concentrically of the anode stem portion 55. Secured to the opposite end of the tubular member 57 is an end wall or closure 58 which defines with the tubular member 57 and end wall 52 a sealed envelope or chamber 59. A heat receiving element 62 formed of copper or other metal of high heat conductivity extends through the end closure 58 and is sealed thereto in a suitable manner, the portion of the element 62 within the chamber 59 being spaced from the anode stem portion 55 and provided with a plurality of heat absorbing fins 63. The portion of the heat receiving element 62 extending outwardly of the chamber is adapted to be connected to a heat absorbing body indicated at 64, such as, for example, by a screw 65. The chamber 59 is substantially filled by a liquid dielec-

tric, indicated at 66, preferably one capable of transferring heat with high efficiency. Preferably space for the vapors of the liquid should be provided as before explained.

As is evident, heat generated at the target of the anode 51 during operation of the tube will be conducted to the stem 55 and transferred through the fins 56 to the liquid 66. The convection currents established in the liquid will effect a flow of the heated liquid past the fins 63 of the heat receiving element 62 to which the heat will be lost and then conducted to the heat absorbing body 64.

Obviously the embodiments of Figs. 1 to 4 are particularly adapted for supporting a tube which is maintained in fixed position relative to the housing or supporting member whereby the liquid convection currents will efficiently effect the transfer of the heat from the hot radiating surfaces to the relatively cold heat absorbing surfaces. It is not to be expected, for example, that a single heat conducting device 9 such as that shown in Fig. 1 would be particularly efficient if the relative position of the X-ray tube and the supporting member 13 were reversed whereby the relatively hot radiating surfaces were at the top rather than at the bottom of the envelope 14. If this occurred, then, of course, the natural convection currents would not establish. On the other hand, if the X-ray equipment and housing is subjected to a relatively great amount of agitation during the operation of the X-ray tube, the consequent movement of the liquid within the envelope 14 may be sufficient to effect the transfer 30 of the heat from the hot to the cold radiating surfaces.

Referring now to Figs. 5, 6 and 7, a preferred arrangement is shown for supporting an X-ray tube 70 within a tubular housing 71 of apparatus wherein the tube and housing rotate relatively about the horizontally disposed, longitudinal axis of the tube. An example of such apparatus is shown in my prior Patent 2,547,996, entitled "Portable X-Ray Unit." The tube 70 comprises an envelope 72 from one end of which projects the anode stem 73, the endmost portion 74 of which is of reduced diameter to provide a shoulder 75 therein. The supporting device, in this instance, comprises a relatively small, metal ring or spool 76 of copper or like heat conductive material having a central aperture in which is received the reduced stem portion 74, the spool being clamped against the shoulder 75 by a washer and screw 77. The screw 77 may also serve as a fastening means for a conductor 78 supplying potential to the anode. The outer periphery of the spool 76 is preferably provided with a plurality of outwardly projecting fins 79 to increase the effective 45 heat radiating surface thereof. Mounted on the inner periphery of the housing 71 in annular relationship to the spool 76 is a ring 82 preferably formed of copper or other heat conducting metal. The ring 82 is shown secured in position by screws 83, though it may be secured to the housing in any suitable manner such as by welding or brazing the same thereto. The inner periphery of the ring 82 is provided with a plurality of inwardly projecting annular ribs or fins 84 to increase the heat absorbing 50 surface thereof. Secured in liquid-tight relation to corresponding sides of the spool 76 and ring 82 are a pair of annular discs or plates 85, 86 formed of glass or other suitable dielectric. The rings 76, 82 and plates 85, 86 define an annular sealed chamber which is filled with an 55 electrically insulating liquid 87 having a high heat transfer efficiency and high dielectric strength, a space for the expansion of the vapors of the liquid being provided as in the previously described embodiments. It will be observed that, whatever the relative rotational position of the housing 71 and X-ray tube 70 about the axis thereof, natural convection currents may readily establish to 60 transfer heat from the spool 76 to the ring 82.

While many liquids are suitable for use in the device of the invention, certain liquid fluorochemicals have been found to be particularly useful because of their chemical 65 and thermal stability and high dielectric strength. Be-

cause of their low viscosity and ability rapidly to establish convection currents, fluoroochemicals such as, for example, heptacosfluorotributylamine, $(C_4F_9)_3N$, and a completely fluorinated cyclic ether having an empirical formula $C_8F_{16}O$ have been found to be particularly suitable. The first of these fluoroochemicals is sold by Minnesota Mining & Manufacturing Company under the trade designation "Fluorochemical N-43" and the latter under the designation "Fluorochemical O-75."

While the invention, for convenience, has been described with particular reference to X-ray apparatus, it is to be understood that its usefulness is not limited thereto.

Having illustrated and described preferred embodiments of the invention, it should be apparent to those skilled in the art that the invention permits of modification in arrangement and detail. I claim as my invention all such modifications as come within the true spirit and scope of the appended claims.

I claim:

1. An electrically insulating device for conducting heat between a pair of members electrically insulated from each other comprising a sealed envelope formed of a dielectric, a pair of spaced-apart elements of a heat conductive material extending into said envelope, the portion of each of said elements within said envelope having a plurality of fins thereon, the portions of said elements protruding from said envelope being adapted to be connected one to each of said members in heat conductive relation therewith, and a nonionizing liquid within said envelope, the volume of said liquid being sufficient substantially to cover said fins in any position of said device, but less than the volume of said envelope to provide expansion space for the vapors of said liquid.

2. An electrical apparatus comprising an X-ray generator including an envelope having a dislike end wall of electrically conductive material, an anode in said generator having a stem portion projecting outwardly through said end wall and sealed thereto in electrically conductive, liquid-tight relation, said stem portion having a plurality of heat radiating fins thereon, a tubular member of a dielectric sealed at one end thereof to the aforementioned end wall in substantially concentric relation with said anode stem portion, a second end wall sealed to the opposite end of said tubular member to define with said tubular member and said aforementioned end wall a sealed chamber, a heat receiving element of heat conductive material extending through said second end wall, the portion of said element within said chamber having a plurality of heat radiating fins thereon, the portion of said element projecting outwardly of said chamber being adapted to be connected to a heat absorbing body, and a liquid dielectric of relatively low viscosity within said chamber and substantially covering said fins.

3. A heat conductive, electrical insulating device for supporting an electrical unit normally operating at an elevated temperature and conducting heat from said unit to a cold body, said device comprising a first metal ring adapted to be secured to a relatively cold body in heat conductive relationship, a second metal ring coaxial with said first ring and adapted to be secured to said unit in heat conductive relationship, a pair of annular discs of electrical insulating material secured to opposite sides of said first and second rings to define therewith a chamber, and a fluid of high heat transfer efficiency and high dielectric strength substantially filling said chamber.

4. In electrical apparatus, having a first member operating at an elevated temperature and at a given potential, and a second member operating at a lower temperature and a different potential and capable of accepting heat generated at said first member, the combination therewith of means to transfer heat from said first member to said second member while maintaining the same in electrically insulated relation, said means comprising means defining a sealed container enclosing a portion of each of said members, said container having a dielectric wall portion electrically insulating said member portions from each other, and a nonionizing liquid of low viscosity and high heat transfer efficiency in said container in contact with both of said member portions whereby said liquid will convey heat from said first member portion to said second member portion.
5. An electrically insulating heat transfer device for use in electrical apparatus having a first element operating at an elevated temperature and at a given potential, 20 and a second element operating at a lower temperature and a different potential and capable of accepting heat generated at said first element, said device comprising a sealed envelope of electrical insulating material, a pair of spaced apart heat conductive members each having a portion within and a portion without said envelope, a nonionizing liquid of low viscosity and high heat transfer efficiency in said envelope in contact with both of said member portions within said envelope whereby said liquid will convey heat between such portions, and means 25 on the said portions of each of said members without said envelope for connecting the same one to each of said elements in heat conductive relationship whereby heat may be transferred through said device from said first element to said second element.
- 35 6. An X-ray apparatus comprising a housing and an X-ray generator having an anode mounted within said housing and operating at a different potential than said housing, the combination therewith of means to transfer heat from said anode to said housing while maintaining the same in electrically insulated relation, said means comprising means defining a sealed envelope, a first heat conductive element mounted on said envelope and having a portion within and a portion without said envelope, the latter portion being connected in heat conductive relation to said anode, a second heat conductive element mounted on said envelope and having a portion within said envelope spaced from the corresponding portion of said first element and a further portion without said envelope, means connecting the latter of said portions to said housing in heat conductive relation, and a nonionizing liquid of low viscosity and high heat transfer efficiency in said envelope in contact with both of said element portions therein whereby heat from said anode will be conveyed through said device to said housing.
